UNITED STATES PATENT OFFICE.

JOHN WILLIAM JEFFRIES, OF PATTONSBURG, MISSOURI.

PORTABLE FIRE-ESCAPE.

No. 920,956.

Specification of Letters Patent.

Patented May 11, 1909.

Application filed June 27, 1908. Serial No. 440,740.

To all whom it may concern:

Be it known that I, JOHN WILLIAM JEFFRIES, a citizen of the United States, residing at Pattonsburg, in the county of Daviess and State of Missouri, have invented certain new and useful Improvements in Portable Fire-Escapes, of which the following is a specification, reference being had therein to the accompanying drawing.

10 My present invention relates to improvements in portable fire-escapes, the main object of my invention, being the provision of a portable frame-work, which is kept readily accessible within a room of a building, 15 and which can be quickly placed at a window or proper exit in the wall, and project a flexible ladder, whereby the occupants may safely leave the burning or endangered building.

20 To attain these objects, the invention consists primarily of a frame-work having adjustably mounted near its upper end a pair of brackets, in which is journaled the flexible ladder and its retaining drum, while in the 25 lower end of the frame work, I provide a sill engaging means, which holds the frame work in rigid position when in use.

To more clearly illustrate my invention, attention is invited to the accompanying 30 drawings, in which:—

Figure 1 is a perspective view of the complete fire-escape, the ladder being upon its drum. Fig. 2 shows the escape in use at a window. Fig. 3 is a detail view of the ladder 35 supporting bracket and drum, and Fig. 4 is a detail view of one of the sill engaging hooks.

Referring to the drawings:—The numeral 1 designates the two long vertical strips or bars, which are spaced and held apart at the 40 top by the transverse strip 2, which extends beyond each strip 1, and at the bottom by means of the round rods or rungs 3 and the two cross-bars 4. When this frame is out of use, it is adapted to stand vertically upon its 45 rollers or casters 5, and lean against the wall within the room, and accessible to a window or other opening in the wall.

Secured adjustably by means of the bolts 6, to the strips or bars 1, and projecting upon 50 one side thereof, are the two brackets 7, which have journaled in their outer ends 8, the shaft 9, of the drum 10, which carries the flexible ladder 11. In order to wind the ladder upon the drum, I employ the handle or 55 crank 12, and to hold the drum at any desired position; I employ the pawl and ratchet

13. By this construction, and by examining Fig. 2, it will be seen that the frame remains upon the inside of the window, while the drum and ladder are projected exteriorly of 60 the same, so that the ladder will pass down in front of the window, and the windows directly below, so that occupants may step upon the rungs 3, through the window and upon the ladder, and with their back to the 65 building can very readily descend safely. In order to hold the frame against slipping, I employ the two pivotally and adjustably mounted sill engaging hooks or arms 14, which are secured to the strips 1, so that 70 their hooked ends will engage the outer face of the window sill or wall, and thus prevent the lower end of the frame, when weight is placed upon the ladder and brackets, from sliding back into the building and thus precipitating the escape through the window.

By this construction of a portable fire-escape, it will be seen that one may be kept in either of the top story rooms, or in each room of a building, and that by reason of its simplicity, the occupants may quickly place the frame in position at the window and let the ladder down upon the exterior of the wall. Thus I produce a simple, durable and inexpensive portable fire-escape, which is thoroughly efficient and practical.

What I claim, as new, is:—

1. In a portable fire-escape, the combination of a frame adapted to parallel the inner wall of a building and project above and below an opening or window therein, brackets carrying a drum and flexible ladder carried by said frame and adapted to be projected through said opening or window, and means for engaging the sill of the opening, as and for the purpose set forth.

2. In a portable fire-escape, the combination of a frame adapted to parallel the inner wall of a building and project above and below an opening or window therein, brackets 100 adjustably mounted upon the frame and adapted to project through the opening or window, a drum journaled in said brackets, a flexible ladder mounted upon said drum and adapted to parallel the exterior of the building, and means carried by the frame and adapted to engage the lower edge of the opening or window, for the purpose set forth.

3. In a portable fire-escape, the combination of a frame adapted to parallel the inner wall of a building and project above and below an opening or window therein, brackets 110

carrying a drum and a flexible ladder carried by said frame and adapted to be projected through said opening or window, and a pair of pivoted hooks connected to the frame and adapted to engage the sill or the opening or window and hold the frame in parallel position.

4. A portable fire-escape, comprising two parallel vertical strips, a transverse strip at the top projecting beyond the vertical strips, cross-bars securing the lower ends of the vertical strips, two rungs mounted in the lower

ends of the vertical strips, two brackets adjustably secured to the vertical strips, a drum and a flexible ladder carried thereby, 15 and a pair of pivoted hooks adjustably secured to the vertical strips near their lower ends, as set forth.

In testimony whereof I affix my signature in presence of two witnesses.

JOHN WILLIAM JEFFRIES.
